(57) **CLAIM**

The ornamental design for a sconce as shown and described.

DESCRIPTION

FIGS. 1 and 2 are front perspective views of a sconce showing my new design;

FIG. 3 is right side view thereof;

FIG. 4 is a front elevational view thereof;

FIG. 5 is a left side view thereof;

FIG. 6 is a rear view thereof;

FIG. 7 is a top plan view thereof;

FIG. 8 is a bottom view thereof; and,

FIG. 9 is an enlarged view of a knob of the sconce shown in FIGS. 1-8 showing the surface ornamentation thereof; all three knobs of said sconce having the same surface ornamentation as that of the knob shown in FIG. 9.

1 Claim, 5 Drawing Sheets
